DESIGN FOR A COMBINED DIAL AND PANEL FOR BATTERY TESTERS

John Harold Kolseth, Newark, N. J., assignor to
Atlas Supply Company, Newark, N. J., a corpo-
ration of Delaware

Application September 9, 1937, Serial No. 71,529

Term of patent 7 years

To all whom it may concern:

Be it known that I, John Harold Kolseth, a citizen of the United States, residing at Newark, New Jersey, have invented a new, original, and ornamental Design for a Combined Dial and Panel for Battery Testers, of which the following is a specification, reference being had to the accompanying drawing, forming part thereof.

Fig. 1 is a front elevation of a combined dial

and panel for battery testers, showing my new design.

Fig. 2 is a side elevation thereof.

Fig. 3 is a top plan view thereof.

I claim:

The ornamental design for a combined dial and panel for battery testers, as shown.

J. HAROLD KOLSETH.
